UNITED STATES PATENT OFFICE.

BURTON HERBERT GEDGE, OF ANDERSON, INDIANA.

ROOFING MEMBER.

1,088,815.

Specification of Letters Patent. Patented Mar. 3, 1914.

Application filed June 10, 1913. Serial No. 772,907.

To all whom it may concern:

Be it known that I, BURTON H. GEDGE, a citizen of the United States, residing at Anderson, in the county of Madison and State 5 of Indiana, have invented a new and useful Roofing Member, of which the following is a specification.

The object of my invention is to produce a roofing of members of sheet material of such 10 form that they may be readily produced by the ordinary sheet metal worker's tools and such that when placed in position with adjacent edges overlapping it will prevent the water from creeping back through the joint.

15 The accompanying drawings illustrate my invention.

Figure 1 is a fragmentary perspective view showing the form of the sheet and the manner of placing same, the sheet in this 20 position having its main body plain or flat with opposite edges formed in accordance with my invention; and Fig. 2 is a similar view of the embodiment of my invention in corrugated sheet material.

25 In the drawings 10 indicates the main body of the sheet provided along one edge with a V-shaped rib formed by the upwardly inclined portion 11 and the downwardly inclined portion 12, said rib being so formed 30 as to straddle and fit the wooden strip 13 which is applied to sheathing 14 at the time the roofing sheet is placed in position. At its opposite edge sheet 10 is provided with upwardly inclined portion 15, and an adjacent downwardly inclined portion 16 which 35 terminates in an in-turned lip or edge 17 which preferably lies nearly or quite at right angles to the portion 16 and has a height exceeding the thickness of a column of water. 40 maintainable between adjacent surfaces of the roofing member by capillary attraction. The angle of inclination of the portion 15 is substantially the same as the angle of inclination of the portion 12 and the height of 45 this portion 15 is such that the portion 16 at its highest point lies snugly upon the ridge of the lip 11-12 but the angle of inclination of the portion 16, because of lip 17, is less than that of the underlying portion 11 50 so that when the parts are assembled, as shown in Fig. 1, the free edge of the lip 17 lies closely against the portion 11 of the adjacent sheet and thus forms an air chamber 18 the height of which exceeds the capillary

possibilities between the two sheets. Nails 55 19 are then driven through the portions 16 and 11 and the underlying wooden strip 13 into sheathing boards and, because of the lip 17 lying nearly or quite at right angles to the portion 11 against which it engages, 60 there is no material bending down of the upper sheet portion 16 under the action of the nails. In order to make the parts lie snugly where an upper series of sheets over- 65 lies the lower sheets, the roof layer can, without difficulty, straighten out a short length of lip 17 at the upper corner of the sheet, as indicated at the upper right hand portion of Fig. 1, thus permitting the portions 16 of the lower series of the sheets to flatten down be- 70 neath the lower ends of the upper series.

It will be noticed that the form of the sheet is such that it can be produced by the ordinary machinery and that the sheets will stack snugly for transportation. 75

The structure shown in Fig. 2 is substantially the same as that shown in Fig. 1 the only difference residing in the fact that the main body 10' of the sheet is longitudinally corrugated in an ordinary manner and no 80 wooden strip is required.

I claim as my invention:

1. A roofing member provided adjacent one edge with a longitudinal rib formed by a portion upwardly inclined from the body 85 of the member and an adjacent downwardly oppositely inclined portion, and at the other edge provided with a rib formed by an upwardly inclined portion and an adjacent downwardly and oppositely inclined portion 90 which latter portion extends to the edge of the body of the member and there is provided with a lip turned under substantially at right angles substantially as and for the purpose set forth. 95

2. A roofing, comprising a plurality of members each of which is provided at one edge with a longitudinal rib formed by a portion upwardly inclined from the body of the member and an adjacent downwardly 100 and oppositely inclined portion and is provided at the other edge with a rib formed by an upwardly inclined portion and an adjacent downwardly and oppositely inclined portion which latter portion extends to the 105 edge of the body of the member and is there provided with a lip turned under substantially at right angles to such portion, said

second rib of one member extending over and resting directly upon the first named rib of an adjacent member so that the first portion of said second rib rests upon the second portion of the first rib and the second portion of the second rib is spaced by said lip from the first portion of the first rib.

In witness whereof, I have hereunto set

my hand at Anderson, Indiana, this 4th day of June, A. D. one thousand nine hundred and thirteen.

BURTON HERBERT GEDGE.
